HENRY NIAS AND WILLIAM POSTER, OF BROOKLYN, NEW YORK, ASSIGNEES TO PUBLIC SERVICE CUP COMPANY, OF BROOKLYN, NEW YORK, A CORPORATION OF NEW YORK.

CHECK-CONTROLLED MECHANISM.

1,214,946.

Specification of Letters Patent.

Patented Feb. 6, 1917.

Application filed February 3, 1914. Serial No. 816,241.

To all whom it may concern:

Be it known that we, HENRY NIAS, a citizen of the United States, and a resident of New York, borough of Brooklyn, in the county of Kings and State of New York, and WILLIAM POSTER, a subject of the Czar of Russia, and a resident of New York, borough of Brooklyn, in the county of Kings and State of New York, 5 have jointly invented certain new and useful Improvements in Check-Controlled Mechanisms, of which the following is a specification.

This invention relates to check controlled mechanisms and particularly to that class thereof which is provided for dispensing drinking cups.

Our improvements are particularly directed to certain features of the dispensing device illustrated, described and claimed in the application of Emil A. Claus, filed June 5, 1912, and bearing Serial No. 701793.

The object of our improvements is to provide simplicity of construction and reliability in operation.

Our improvements are illustrated in their preferred form in the drawings accompanying this specification wherein Figure 1 is a sectional elevation on line 1, 1 of Fig. 2. 30 Fig. 2 is a plan view with those parts above line 2, 2 of Fig. 1 removed. Fig. 3 is a sectional elevation of a portion of our improvements, the section being taken on line 3, 3 of Fig. 4. Fig. 4 is a sectional elevation of a detail of our device on line 4, 4 of Fig. 5, but in a different position and showing some additional parts. Fig. 5 is a detached plan view of a portion of what is shown in Fig. 2, and Fig. 6 is a detached 35 plan view of a detail of Fig. 5. Figs. 1 to 3 inclusive are to one scale, and Figs. 4 to 6 inclusive are to another scale and which scale is double that of Figs. 1 to 3.

Before describing the invention in detail 45 we desire to have it understood that the invention is not limited to the particular construction and arrangement of parts which we have illustrated and shall herein-after describe, and that various changes may 50 be made in the mechanism shown without departing from the spirit or scope of the invention, and that the phraseology which we employ is for the purpose of description and not of limitation.

55 The operative parts of our improved

mechanism may be supported on base 5 having a cover 6. Said cover 6 is provided with an upstanding tubular member 7 for the reception of the articles to be dispensed, and which articles in the present instance, 60 are illustrated as paper cups arranged in a stack 8, the lowermost cup 9 of said stack resting upon flanges as 10 of a plurality of rotary escapements as 11, 12. Said escapements are arranged circumferentially about 65 said stack of cups. Each of said escapements is provided with a pinion as 13, for engagement with a rotary rack or internal gear 14. Each of said escapements is also provided with a wedge shaped circumferential member 32 which, when said escapements are rotated, enters between the flange of the lowermost cup 9 and the flange of that cup directly thereabove. Thus said escapements are operable at one time for supporting the stack of cups by means of flanges 10, and at another time for supporting all of the cups in the stack except the lowermost one, by means of members 32, and also for separating that lowermost cup 80 from the stack by means of said wedging members 32.

Internal gear 14 is in the form of a rotatable ring having teeth for engagement with the several pinions 13 of said escapements, and is efficient for rotating those escapements in synchronism. Below said ring 14 and concentric therewith is ring 15 having handle 16, whereby said ring may be manually rotated through a limited arc of 85 movement. Upper ring 14 is guided for rotation by pinions 13, and lower ring 15 is similarly guided by collars 17, downwardly reaching from said pinions respectively. Escapements as 11, 12 are rotatably supported on stems as 18 threaded into base 5. For returning ring 15 to its normal position of Fig. 2, spring 19 is provided, and for returning ring 14 to its normal position, post 20 on ring 15 engages ear 33 of ring 14. 90

Cover 6 is provided with a check or coin slot 21, suitably disposed circumferentially of that cover for registering with the coin receiving members of rings 14 and 15, when those rings are in their normal positions as 105 shown in Figs. 2 and 5, their relative positions being shown in greater detail in said Fig. 5. Furthermore, said cover 6 is of such thickness at those portions thereof surrounding coin slot 21 as to position its 110

lower wall 22 closely contiguous to the upper face of ring 14. Also, the united thickness of rings 14 and 15 is substantially equal to the diameter of the check or coin with which the machine is adapted to be operated, as plainly shown in Fig. 3. By the arrangement just described, a coin or a piece of material, of larger diameter or of such shape as to extend upwardly above the top face of ring 14 sufficiently to extend into coin slot 21, will render the machine inoperative by locking said rings to the coin slot.

The coin engaging portions of rings 14 and 15 are of peculiar construction and adapted to coact in engagement with the coin in a peculiar way. Upper ring 14 has means comprising oppositely disposed walls 23 and 24, for engaging opposite edges of one face of the upper half of a check or coin. Said walls 23 and 24 are in the same vertical plane, and the space therebetween is cut away at 25 to provide an opening thereat. Opposite said opening is wall 26 for engaging the opposite face of said upper half of said coin.

The coin engaging portion of ring 15 comprises projection 27, preferably of hemispherical shape, and said ring 15 is cut away at 28 in front of said projection 27, whereby a pocket is formed between said projection and wall 28. By this construction, when ring 15 is moved in clockwise direction by its handle 16, projection 27 will engage one face of the lower half of a coin or check 29, the upper half of said coin being cramped between walls 23 and 24 on the one hand and wall 26 on the other hand, of ring 14. The continued movement of ring 15 will cause ring 14 to move therewith through the instrumentality of said coin 29.

If, however, a piece of yieldable material such as paper or cardboard be inserted through slot 21 into engagement with the coin engaging faces of rings 14 and 15, and handle 16 be thereupon pulled forwardly, Fig. 2, said yieldable material will be so bent or folded as to be inefficient for moving ring 14 from ring 15. Or, if a stick such as a portion of a match splint be inserted through opening 21, it will likewise be inefficient for moving ring 14 from ring 15.

When a suitable coin is inserted as shown in Figs. 3 and 4 and handle 16 is pulled its full stroke, said coin will be delivered over aperture 30 in base 5, Fig. 4, and upon the releasing of said handle, said coin will fall through that aperture into some suitable receptacle, not shown.

In assembling machines of this character, it usually requires special skill to suitably time the escapements as 11, 12 with the internal gear teeth on ring 14. For enabling a person to assemble the escapements and internal gear teeth with precision and uni-

formity, we have provided each of the gear portions of ring 14 with a tooth 31 thicker than the other teeth, for engagement with the correspondingly wider space 34 in each of said escapements as 12. By this means, an unskilled person can assemble these parts with accuracy and despatch.

I claim:

1. Check controlled mechanism including in combination two parallel contiguous members each having check engaging means normally in register with each other, the check engaging means of one of said members being adapted for gripping opposite faces of the check upon one side of a given diameter and for holding said check against material deviation from normality to the common plane of said parallel members, and the check engaging means of the other of said members being adapted for impinging upon one side of that portion of said check on the other side of said given diameter at a single point remote from said diameter.

2. Check controlled mechanism including in combination two parallel contiguous members each having check engaging means normally in register with each other, the check engaging means of one of said members being adapted for gripping opposite faces of the check upon one side of a given diameter and for holding said check against material deviation from normality to the common plane of said parallel members, and the check engaging means of the other of said members being adapted for impinging upon one side of a remote portion of said check on the other side of said given diameter whereby one of said contiguous members may be actuated by the movement in one direction or the other of said contiguous members, and means for manually actuating one of said members.

3. Check controlled mechanism including in combination two coaxial and axially contiguous rotatable rings, each having check engaging means normally in register with each other, check guiding means adjacent to one of said rings, the check engaging means of one of said rings being adapted for gripping portions of the check upon one side of a given diameter of said check and the check engaging means of the other of said rings being adapted for impinging upon one side of a remote portion of said check on the other side of said given diameter.

4. Check controlled mechanism including in combination two coaxial and axially contiguous rotatable rings, each having check engaging means normally in register with each other, the check engaging means of one of said rings being adapted for gripping opposite portions of the check upon one side of a given diameter of said check

and for holding said check against deviation from parallelism with the axis of said rings, and a projection on the other of said rings for engaging said check on one side of that portion thereof lying on the other side of said given diameter remote from the gripping portions of said first ring.

5. Check controlled mechanism including in combination two coaxial and axially contiguous rotatable rings, each having check engaging means normally in register with each other, check guiding means adjacent to one of said rings, said check guiding mean terminating closely adjacent to the receiving side of the check engaging means of said ring, and means adjacent to the delivery side of the check engaging means of the other of said rings for normally supporting a check in operative position relatively to said rings, the check engaging means of one of said rings being adapted for gripping opposite portions of the check upon one side of a given diameter of said check and the check engaging means of the other of said rings being adapted for impinging upon one side of a remote portion of said check on the other side of said given diameter.
10. Check controlled mechanism including in combination two parallel contiguous members each having check engaging means normally in register with each other, the check engaging means of one of said members comprising oppositely disposed narrow walls spaced apart for engaging opposite edges of one face of that portion of the check lying upon one side of a given diameter, a wall for engaging the opposite face of said portion, and the check engaging means of the other of said members comprising a projection located and adapted for engaging that face of the portion of said check on the other side of said given diameter opposite the edge-engaged face of the first mentioned portion of said check, at a point remote from said diameter.
15. Check controlled mechanism including in combination two parallel contiguous members each having check engaging means normally in register with each other, the check engaging means of one of said members comprising oppositely disposed narrow walls spaced apart for engaging opposite edges of one face of that portion of the check lying upon one side of a given diameter, a wall for engaging the opposite face of said portion, and the check engaging means of the other of said members comprising a projection located and adapted for engaging that face of the portion of said check on the other side of said given diameter opposite the edge-engaged face of the first mentioned portion of said check, at a point remote from said diameter.
20. Check controlled mechanism including in combination two parallel contiguous members each having check engaging means normally in register with each other, the check engaging means of one of said members comprising oppositely disposed narrow walls spaced apart for engaging opposite edges of one face of that portion of the check lying upon one side of a given diameter, a wall for engaging the opposite face of said portion, and the check engaging means of the other of said members comprising a projection located and adapted for engaging that face of the portion of said check on the other side of said given diameter opposite the edge-engaged face of the first mentioned portion of said check, at a point remote from said diameter.
25. Check controlled mechanism including in combination two parallel contiguous members each having check engaging means normally in register with each other, the check engaging means of one of said members comprising oppositely disposed narrow walls spaced apart from each other for engaging opposite edges of one face

of that portion of the check lying upon one side of a given diameter, a wall for engaging the opposite face of said portion, and the check engaging means of the other of said members comprising a projection located and adapted for engaging one face of that portion of said check on the other side of said given diameter at a point remote from said diameter.

30. Check controlled mechanism including in combination two parallel contiguous members each having check engaging means normally in register with each other, the check engaging means of one of said members comprising oppositely disposed narrow walls spaced apart for engaging opposite edges of one face of that portion of the check lying upon one side of a given diameter, a wall for engaging the opposite face of said portion, and the check engaging means of the other of said members comprising a projection located and adapted for engaging that face of the portion of said check on the other side of said given diameter opposite the edge-engaged face of the first mentioned portion of said check, at a point remote from said diameter.

Signed at New York, borough of Brooklyn, in the county of Kings and State of New York, this 2nd day of February, 1914, before two subscribing witnesses.
